UNITED STATES PATENT OFFICE.

JAMES F. REYNOLDS, OF CRETE, NEBRASKA, ASSIGNOR TO THE AMERICAN RAILWAY DEVICE CO., A CORPORATION OF ARIZONA TERRITORY.

AUTOMATIC BRAKE-SETTING MECHANISM.

977,967.

Specification of Letters Patent.

Patented Dec. 6, 1910.

Application filed September 10, 1909. Serial No. 517,350.

To all whom it may concern:

Be it known that I, JAMES F. REYNOLDS, a citizen of the United States, residing at Crete, in the county of Saline and State of Nebraska, have invented new and useful Improvements in Automatic Brake-Setting Mechanism, of which the following is a specification.

This invention relates to a device for 10 automatically operating or actuating the brake setting mechanism of a moving train when it approaches a point of danger such as an open switch, a bridge or the like, thereby relieving the engineer of the responsibility of setting the brakes at such points by performing the work automatically and 15 without fail.

A further object of the invention is to 20 provide the air pipe of a train with a relief valve having an operating arm or lever that projects in the path of a member supported alongside the track so as to automatically open the valve at a predetermined point.

A still further object of the invention is 25 to provide suitable and convenient means arranged alongside the railroad track for the purpose of engaging and actuating the air relief valve, such engaging mechanism being of various types as will be hereinafter 30 described.

Still further objects of the invention are to simplify and improve the general construction and operation of this class of devices.

With these and other ends in view which 35 will readily appear as the nature of the invention is better understood, the same consists in the improved construction and novel arrangement and combination of parts which will be hereinafter fully described and particularly pointed out in the claim.

In the accompanying drawings has been 40 illustrated a simple and preferred form of the invention, it being however understood that no limitation is necessarily made to the precise structural details therein exhibited but that changes, alterations and modifications within the scope of the invention may be resorted to when desired.

In the drawings: Figure 1 is a plan view 45 showing a portion of a railroad track including the switch and illustrating one form of the invention arranged in proximity to the switch. Fig. 2 is a transverse sectional view on a larger scale taken on the plane indicated by the line 2-2 in Fig. 1. Fig.

3 is a vertical sectional view taken approximately at right angles to Fig. 2 and on the plane indicated by the line 3-3 in said figure. Fig. 4 is a sectional elevation showing certain parts of the device adjacent to the 60 switch. Fig. 5 is a front elevation of a locomotive showing the same approaching the brake setting mechanism.

Corresponding parts in the several figures are denoted by like characters of reference. 65

A post or upright 10 supported upon a base 11 which may be suitably secured upon one of the ties adjacent to one of the track rails 12, as shown in Fig. 1 is provided with bearings for a pin or shaft 13 disposed approximately parallel to the track rail and carrying a lever L having two arms one of which 14 extends in the direction of the track while the other arm 15 which extends in the opposite direction is equipped with 75 a weight 16 the gravity of which tends to hold the arm 14 in an approximately horizontal position, the upward movement of the arm 14 being limited by a suitably disposed stop not shown; a hood or cover, 18, 80 is suitably arranged to exclude snow, ice and the like. This cover which may be regarded as being mounted upon the shaft 13, which latter extends through the sides thereof, is provided with flanges 17 supported 85 upon the upper edge of the lever L so that the cover will rock or move with said lever, and thus without occupying much space, will serve to form a protection for the joint to prevent the entrance of moisture and the 90 formation of rust and the admission of obstructions, whereby the free operation of the device might be interfered with, this being obviously of great importance since the weight 16 is depended upon to move the 95 lever into operative position when desired.

The lever L is also provided with a downwardly extending arm or crank 21; with this arm crank is connected one end of a suitably guided flexible element 22, the other end of which is connected with a drum 23 upon a shaft 24 that is supported for rotation in a switch stand 25 or in some other suitable supporting casing; the arrangement being such that when the switch is operated either to open or to close the same, the drum-carrying shaft 24 will be partially rotated by means of a crank 26 upon said shaft being suitably connected with the switch tongues by a link 27 or in any other suitable conven- 110

- ient and well known manner. When the switch is closed, the flexible element 22 will be partially wound upon the drum 23, thus oscillating the rock shaft 13 which constitutes the fulcrum of the lever L against the gravity of the weight 16 and moving the arm 14 in a downward direction to the non-obstructing position shown in dotted lines in Fig. 2; when the switch is thrown open, 10 the flexible element 22 is unwound from the drum, and the rock shaft 13 will be oscillated by gravity of the weight 16, thus lifting the arm 14 to the obstructing position shown in full lines in Fig. 2.
- 15 The air pipe 30 of a train is provided with a branch 31 having a relief valve 32, the stem of which 33 is provided with a lever 34 which, when the valve is closed, occupies an approximately vertical position, a portion 20 of said lever extending downwardly in the path of the arm 14 when the latter is raised to an obstructing position. When a train thus equipped approaches the brake actuating mechanism, and the latter is set 25 with the arm 14 in an obstructing position, said arm upon engaging the lever 34 will oscillate the valve stem 33, thus opening the valve and permitting air to escape, thus causing the setting of the brakes. When the 30 main line is open, the arm 14 will be in a non-obstructing position as will be readily understood and no operation will ensue excepting the event of the breakage of parts, such as the flexible element 22, when the 35 brake actuating mechanism will be automatically set by gravity of the weight 16.

From the foregoing description, taken in connection with the drawings hereto annexed, the operation and advantages of this invention will be readily understood. 40

The construction of the improved brake setting mechanism is simple and it may be installed at a moderate expense; its operation is not only safe and sure, but is, apart from the initial setting, entirely automatic 45 and not dependent upon the watchfulness of the employees.

Having thus described the invention, what is claimed, is:—

In a device of the character described, a 50 supporting member such as a post or upright supported adjacent to a railroad track, a shaft extending therethrough, a lever fulcrumed upon the shaft and having one arm extending in the direction of the track and 55 an oppositely extending arm carrying a weight, a hood supported upon the lever and having side members engaging the shaft, which latter extends through said side members, a crank extending downwardly from the lever, and means connected with said crank to rock the lever against the gravity of the weight, said means including a flexible element connected with the crank, and a suitably supported winding drum for the 60 flexible element.

In testimony whereof I affix my signature in presence of two witnesses.

JAMES F. REYNOLDS.
